LOCOMOTIVE BOILER

Charles Gilbert Hawley, Chicago, Ill., assignor to
Locomotive Firebox Company, Chicago, Ill., a
corporation of Delaware

Application November 5, 1931. Serial No. 573,044

37 Claims. (Cl. 122—58)

This invention relates to improvements in locomotive boilers and it consists of the matters hereinafter described and more particularly pointed out in the appended claims.

5 The invention is particularly concerned with boilers of the kind embodying grateless fireboxes in which fuel such as oil or powdered coal is burned in suspension therein, the firebox being substantially wholly bottomed by inwardly and 10 downwardly extending flat water steaming and circulating elements.

The primary object of the invention is to provide an improved arrangement of the parts more or less associated with said water steaming and 15 circulating elements wherein there is no direct and contacting engagement between the ends of said elements and the refractory material forming the burner and flash walls of the firebox whereby passageways are provided for the air necessary to support combustion and which air is 20 distributed in its entrance to the firebox to provide more efficient combustion.

Another object of the invention is to provide an improved arrangement for the inner and adjacent, though spaced bottom margins of said elements, wherein air is better distributed for combustion purposes without a localization of such air at any one point in its entrance into the firebox in the space between said elements.

30 A further object of the invention is to so arrange the parts of the water steaming and circulating elements with respect to the burner wall and bottom closure pan for the firebox, that air chambers are provided between said elements and 35 pan, wherein the secondary air necessary to support combustion is preheated by said elements before it is admitted to the firebox proper for combustion purposes.

Another object of the invention is to so arrange 40 the elements in the firebox that mud chambers of greater capacity are provided at the rear ends of the side water legs, out of the zone of influence of the high temperature in the firebox so that instead of hardening and thus adhering to the associated sheets, it remains soft and slushy for easy 45 flushing.

Still another object of the invention is to so dispose the elements in said firebox that they will have an inclination giving a natural flow of 50 boiler water which promotes circulation at the rear end of said element.

Still a further object of the invention is to provide means carried by the ends of said elements, which are adjustable whereby the desired dimensions of the air inlet crevices or slots between the

ends of said elements and the associated burner and flash walls are easily obtainable.

Still another object of the invention is to provide a construction of this kind wherein the parts are so disposed as to present sufficient area of the inside throat sheet of the firebox permitting the easy attachment of the neck of a thermic siphon should it be desired to install such a siphon in the firebox.

The above mentioned objects of the invention, 65 as well as others, together with the many advantages thereof, will more fully appear as I proceed with my specification.

In the drawings:—

Fig. 1 is a longitudinal vertical sectional view 70 through the firebox end of a locomotive boiler embodying my invention.

Fig. 2 is a transverse vertical sectional view 75 through the same as taken on the line 2—2 of Fig. 1 looking toward the burner wall end of the firebox.

Fig. 3 is another transverse vertical sectional view through the bottom rear end part of the firebox as taken on the line 3—3 of Fig. 1, looking 80 toward the flash wall end of the firebox.

Fig. 4 is a detail fragmentary view in bottom plan, on an enlarged scale, of the front end of the water steaming and circulating elements and associated parts.

Fig. 5 is a detail vertical sectional view through 85 parts shown in Fig. 4 as taken on the line 5—5 of Fig. 4.

Fig. 6 is a detail transverse vertical sectional view similar to Fig. 3 illustrating a modified form of water steaming and circulating element.

Fig. 7 is a detail transverse vertical sectional view similar to Fig. 2 and shows a further modified form of water steaming and circulating element.

Fig. 8 is a diagrammatic, horizontal, plan sectional view through the firebox on a reduced scale as taken on the line 8—8 of Fig. 1 and illustrates more particularly the shape of the air inlet slot between said water steaming and circulating element when arranged in the manner shown in Figs. 1 and 2.

Fig. 9 is a view similar to Fig. 8 wherein the air inlet slot between said elements converges from the rear end toward the front end of the firebox.

Fig. 10 is a view similar to Fig. 8 wherein the air inlet slot between said element converges from the front end toward the rear end of the firebox.

In general, my invention contemplates the provision of a pair of flat, hollow water steaming

and circulating elements that extend downwardly and forwardly from the inner rear sheet of the firebox toward the front thereof, as well as downwardly and inwardly from each side sheet 5 with which it communicates. Said elements terminate in a substantially close spaced relation to provide a central longitudinal air inlet slot between the inner sides of said elements along the median plane of the firebox. The front and rear ends of the firebox are closed by a burner wall and a flash wall respectively, each spaced from the associated ends of said element thereby leaving transversely extending front and rear end air inlet slots.

Between said burner and flash walls, below said elements and extending from one side of the firebox to the other, is a bottom pan or closure, which coacts with said wall to provide an air preheating chamber beneath said elements and with which the slots above mentioned communicate. Secondary air is admitted into this chamber through suitable door controlled openings in the burner wall and after being heated therein by contact with the bottom walls of said elements, passes through said slots into the firebox to support combustion therein and as these slots are disposed at the ends and along the median line of the firebox, a better distribution of air for such combustion purposes is afforded. The elements carry at their ends adjustable plates whereby the width of said end slots may be carefully determined, thus providing that amount of air yielding the highest efficiency in combustion.

By inclining the elements in the manner above mentioned, a greater portion of the inside throat sheet, above the burner wall is exposed for the attachment of the neck of an associated siphon or siphons. Furthermore such an inclination leaves larger and deeper mud chambers at the rear ends of the side water legs wherein the mud remains soft and may be easily flushed out and again such inclination provides a more natural water flow toward the rear ends of said elements so that circulation is thereby increased.

Referring now in detail to that embodiment of the invention illustrated in the accompanying drawings and especially to Figs. 1, 2, 3 and 4 thereof:—1 indicates the barrel of the boiler in the rear end of which is provided the usual firebox 2. Said firebox is constituted by the front or flue sheet 3, rear sheet 4, side sheets 5—5 and crown sheet 6 and the bottom portion of the flue sheet is formed to provide the inside throat sheet 7. The firebox wrapper comprises the top plate 8, the side plates 9, outside throat plate 10 and outside back plate 11.

The wrapper together with the firebox sheets described, provide the several water legs of the boiler, that is, the side water legs 12, the front leg or throat 13 and the back leg 14 all bottomed by a mud ring 15. The firebox sheets are joined to the wrapper by means of the usual staybolts and the rear sheet 4 and the back plate 11 are formed to provide a door opening 16 which is normally closed.

The firebox structure above described may be taken as typical of standard practice and includes all essential parts except the grate which, of course, when fuel is burned in suspension is omitted and the open bottom of the firebox is closed as will later appear.

In the open bottom of the firebox is located a pair of flat hollow water steaming and circulating elements or walls 17—17 respectively, each 75 of which is connected along one side to an associ-

ated side sheet 5 and extends downwardly and forwardly at an inclination considerably greater than that of those parts of the mud ring 15 closing the bottom of the side water legs 12. Said elements also extend downwardly and inwardly from their associated side sheets. Each element is substantially and conveniently rectangular in plan and is longer than it is wide and is open at one side and is closed at its other side as well as at its ends. Each element comprises, in this instance, relatively straight, flat, top and bottom staybolted walls 18 and 19 respectively and front and rear end walls 20—21 and that side of said element opposite its open side is closed by a rounded wall 22. The rounded walls 22 of both elements are quite closely spaced to provide a longitudinally extending air inlet slot 23 in the median plane of the firebox. The open side of each element is defined by flanges 17a which are butt welded as at 17b in suitable openings provided in the inside sheets 5 of the firebox, as best shown in Fig. 1.

It will be observed from Fig. 1 of the drawings that the ends of said elements stop short of the ends of the firebox as defined by the throat sheet 7 and rear sheet 4 to there leave spaces which are closed by suitably supported refractory walls preferably of fire brick. Associated with the front end of the elements and extending across the firebox is one of such walls that forms the front or burner wall 24 and associated with the rear end of said elements and also extending across the firebox is the rear or flash wall 25. Said walls are spaced a short distance from the ends of said elements to form transversely extending end air inlet crevices or slots 26—27 respectively between said element ends and said walls. Not only are said crevices or slots thus provided, but another advantageous feature is that no abrasive action can take place between the ends of said elements and walls should any relative movement occur between them under expansion or contraction due to temperature changes. Furthermore, strains are, in this way, avoided.

To easily define the most effective width of said end slots, so far as the entrance of air therethrough is concerned for assisting in sustaining combustion, I may provide along the end of the bottom plate 19 of each element, a plurality of 125 studs 28 and mounted thereon are strip members or plates 29 having transverse slots 30 through which said studs extend. Upon said studs are threaded nuts 31 all as best shown in Fig. 4. By loosening said nuts, said strip members 29 may be moved toward or away from the associated wall 24—25 to give the desired width of slot 26—27 respectively. With such an arrangement, it is not necessary to work to such close tolerances and therefore, one size of element may be applied to fireboxes of different lengths.

The entire bottom of the firebox below said elements is closed by a pan 32 which extends from the burner wall to the flash wall and from one side to the other of the firebox. This pan is provided on its top surface with a suitable refractory insulating lining 32', preferably of asbestos, and in said pan in line with each stud 28 is a hole 33 which may be opened and closed by a pivoted cover 34. By means of such an arrangement, it is apparent that access may be had to the nuts 31 for actuation when necessary. The pan follows the inclination of the elements and is, therefore, deeper or lower at the front end than at the rear end. While it is preferable that the holes 33 be 150

closed, this is not essential as they may be left open.

Each element is provided at its inner foremost corner, which corner is the lowest in elevation, 5 with a blow-off connection 34' which, in connection with washout plugs 35 in the sheets 9, in line with the mouth of said elements, permits the ready cleaning of said elements.

In the burner wall, in line with the air inlet slot 23, before mentioned, is located an opening 35' into which projects a fuel nozzle 36 by which fuel, such as oil, may be fed into the firebox, above the elements therein. A portion of the air, necessary to support combustion, enters the firebox through said opening. Also disposed in said burner wall, preferably to each side of the opening 35 and below said elements, are the secondary or auxiliary air inlet openings 37 which open into each side of the air chamber, before mentioned. Entrance of air, through said openings, may be controlled by damper-like doors 38. Each door is mounted upon a perpendicular shaft 39 that extends down through the pan 32 and each is provided with an arm 40. The arms of both doors are suitably connected with linkage by which said doors may be operated from the cab of the locomotive.

In the present instance, I have shown a pair of siphons 41 in the firebox and each siphon includes a perpendicularly disposed, substantially triangularly shaped, flat, hollow staybolted body 42. The elongated top end of each siphon body is open and is welded in a suitable opening in the crown sheet while the bottom end of said body terminates in a tubular neck 43 connected to a suitable diaphragm 44 in the inner throat sheet just above the horizontal portion of the burner wall. Of course, the number of such siphons employed in a firebox is dependent upon the width of the firebox and when a pair of such siphons are employed, they are disposed one upon each side of the median line of the firebox.

In that form of my invention in which the elements terminate in such spaced relation as to provide a uniform narrow slot-like air inlet 23, as best shown diagrammatically in Fig. 8, the elements are not truly rectangular in shape. However, they can be made in different shapes, if desired. Thus, they may be made so that the longitudinal slot between the elements increases in width toward the rear end, as shown diagrammatically at 23a in Fig. 9, or so that it increases in width toward the front end, as shown diagrammatically at 23b in Fig. 10.

Instead of the elements being straight flat ones, as shown in Figs. 2 and 3, they may be made with a reversed curved formation, as indicated at 17b in Fig. 6.

In Fig. 7, is illustrated a further modified form of construction wherein the inner closed ends of the elements are made with a bulge 22a. With such a construction it is preferable to space said bulges a greater distance apart to provide a wider air inlet 23c.

In connection with any of the structures, I may provide fire bricks 45 having tapering sides which rest upon the closed sides of the element. Said tapering sides of the fire brick may be provided with grooves 46 through which air may enter from the inlet 23c, into the firebox. These bricks, of course, reach a high temperature and should the nozzle 36, which atomizes the fuel, discharge droplets of the same, these droplets will fall upon said bricks and will be immediately vaporized.

Thus, waste of fuel and carbonizing and fouling are reduced.

In operation, with the fuel forced into the firebox, through the nozzle 36, primary air enters through the nozzle opening 35'. Secondary or auxiliary air enters the air chamber beneath the elements 17 through the openings 37 and this air is preheated in said chamber by contact with the various heated surfaces thereof. A part of this heated secondary air enters the firebox to assist in combustion, not only through the longitudinal median slot 23 but also through the transverse end slots 26, 27. Thus, instead of but a single air inlet at the center of the firebox, the air enters at different points whereby a better distribution is provided for the same so that a cleaner and more efficient combustion results.

The intense heat from the fuel burning in suspension over those portions of the elements exposed thereto, causes a rapid absorption of heat by the top wall parts thereof, which in turn, passes to and is absorbed by the water in the upper half of said elements, greatly increasing the temperature thereof and converting some of it into steam. Because of the upward and outward inclination of said elements, a like flow is imparted to this exceedingly hot water, colder water from the side water legs flowing along the bottom wall of the element toward the closed sides of the elements. Because of the upward 100 and rearward inclination of said elements, a greater gravitation action of the water is felt in said elements, whereby circulation as indicated by the arrows is increased to an appreciable extent.

Also, counter currents are set up in the elements, as indicated by the arrows in Figs. 2 and 3, so that colder water passes into each element through its lower open end and along its bottom wall, while the extremely hot water and steam 110 passes out of each element along its top wall, chiefly toward the upper or rear end of the element, which is exposed to the products of combustion burning in suspension in the firebox.

By the arrangement described, a better circulation of boiler water in the side water legs is established and this circulation is also apparent in the front and rear water legs along the bottom because of the rush of water therefrom into said elements along and just above the mud ring. 120 Thus the elements described, each of which has only one common or combined inlet and outlet, not only increase the active water heating surface of a firebox of this kind but insure a condition in the various water legs which eliminates 130 any still or quiet area of water therein, with the result that there is less scale accumulation which would retard heat absorption by the water in said legs.

It is apparent that the highest temperature 130 and greatest flame volume which can radiantly effect the surfaces or walls of said elements exposed thereto, is at that end of the firebox opposite the fuel nozzle. This higher temperature at said end of said element will cause acceleration of the upward circulation at said end and a corresponding downward acceleration at the other end of the element. Thus in connection with the water movement, inward and downward along the bottom wall of the element and outward and upward along the top wall, there is also provided a longitudinal flow of water toward the hotter end of the element which materially assists in the better distribution of water in the water legs and the lodging of sludge and 140 150

sediment in the bottom end portions of the elements from which it can be easily flushed.

It is also apparent that the flame of the fuel burning in suspension substantially fills the firebox and envelopes the entire outer surface of the siphons. The water therein is heated to an extremely high temperature and a part thereof is converted into steam and this passes out through the top opening of the siphon into the boiler water and steam space. The colder water at the bottom of the boiler enters the inlet neck of the siphon and thus induces a water movement through the siphon that produces a fore and aft circulation in the boiler.

15. This circulation in connection with the circulation through the side water legs, as produced by the elements as before described, results in a complete interchange of water throughout all parts of the boiler.

20. The construction described, readily permits the conversion of a coal burning locomotive to one burning fuel in suspension with but a small amount of labor and material and the reconversion back into a coal burner may also be readily made. As the elements are supported solely by the various flanges, thereof, from the side sheets, it is apparent that they may flex to come and go with the contraction and expansion due to temperature changes. In those structures wherein bricks 45 are employed, as such bricks are loose and merely rest on the adjacent sides of the elements, they can shift to the extent necessary to accommodate the movement of the elements as before mentioned.

35. It will be understood that some of the brick 45 which span the space 23c between the bulges 22a of adjacent elements may omit the air grooves 46. In this way it is possible further to regulate the air supply and properly adjust it to the particular installation.

40. While in describing the invention, I have referred in detail to the form, arrangement and construction, of the various parts thereof, the same is to be considered merely as illustrative, and therefore, I do not wish to be limited thereto except as may be specifically set forth in the appended claims.

I claim as my invention:

1. A locomotive boiler embodying therein a firebox having side sheets defining the inner sides of side water legs, said side water legs being closed at the bottom, a hollow water circulating and steaming bottom therefor having oppositely inclined transversely disposed portions which are fixed in the respective side sheets and which open into respective side water legs, said hollow water circulating and steaming bottom extending longitudinally of the firebox at an angle to the horizontal and to the plane of the bottom, closure of the side water legs, and a burner positioned to discharge fuel for burning in suspension over said hollow water circulating and steaming bottom.

2. A locomotive boiler embodying therein a firebox having side sheets defining the inner sides of side water legs, a pair of hollow water circulating and steaming elements, each open along one side, said open side being fixed in an associated side sheet, each said element being inclined transversely of the firebox, longitudinally of the firebox and particularly fore and aft with respect to the plane of the side water leg, and a burner positioned to discharge fuel for burning in suspension over said elements.

75. 3. A locomotive boiler embodying therein a

firebox having side sheets defining the inner sides of side water legs, a pair of hollow water circulating and steaming elements, each open along one side, said open side being fixed in an associated side sheet, so that it is inclined downwardly and inwardly transversely of the firebox and fore and aft at an angle to the horizontal and to the plane of the bottom of the side water leg longitudinally of the firebox, and a burner positioned to discharge fuel for burning in suspension over said elements.

4. A locomotive boiler embodying therein a firebox having side sheets, a pair of hollow water circulating and steaming elements, each closed along one side and both ends, and open along the other side and which latter is fixed in an associated side sheet, so that it is inclined downwardly and inwardly transversely of the firebox and upwardly and rearwardly longitudinally of the firebox with respect to the bottom of the side water leg, and a burner positioned to discharge fuel for burning in suspension over said elements.

5. A locomotive boiler embodying therein a firebox having side sheets defining the inner sides of side water legs and front and back sheets, front and back walls arranged adjacent the front and back sheets, and a hollow water circulating and steaming bottom for the firebox having side portions opening into the side water legs, said water bottom being of less length than the distance between said front and back walls, thereby forming air feeding slots, and a burner positioned to discharge fuel for burning in suspension over said hollow water bottom.

6. A locomotive boiler embodying therein a firebox having side sheets defining the inner sides of side water legs and front and back sheets, front and back walls arranged adjacent the front and back sheets, and a hollow water circulating and steaming bottom for the firebox having side portions opening into the side water legs, said water bottom being of less length than the distance between said front and back walls, thereby forming air feeding slots, means for controlling the area of said slots, and a burner positioned to discharge fuel for burning in suspension over said hollow water bottom.

7. A locomotive boiler embodying therein a firebox having side sheets defining the inner sides of side water legs and front and back sheets, front and back walls arranged adjacent the front and back sheets, a hollow water circulating and steaming bottom for the firebox having oppositely inclined transversely disposed portions, which are fixed in the respective side sheets, and which open into respective side water legs, said water bottom extending longitudinally of the firebox at an angle to the bottom of the side water legs, and said water bottom being of less length than the distance between said front and back walls, thereby forming air feeding slots, and a burner positioned to discharge fuel for burning in suspension over said hollow water bottom.

8. A locomotive boiler embodying therein a firebox having side sheets defining the inner sides of side water legs and front and back sheets, front and back walls arranged adjacent the front and back sheets, a pair of hollow water circulating and steaming elements, each open along one side, said open side being fixed in an associated side sheet, and each element being inclined transversely of the firebox and inclined longitudinally with respect to the horizontal and

- to the plane of the bottom of the side water leg, said elements being of less length than the distance between said front and back walls, thereby forming air feeding slots, and a burner positioned to discharge fuel for burning in suspension over said hollow water bottom. 5 to the bottom of the side water leg longitudinally of the firebox, a closure extending across the firebox under and in spaced relation to the hollow water circulating and steaming bottom, thereby forming an air preheating chamber, a burner positioned to discharge fuel for burning in suspension over the hollow water circulating and steaming bottom, and an opening for admitting air from said preheating chamber to the combustion chamber. 80
9. A locomotive boiler embodying therein a firebox having side sheets defining the inner sides of side water legs and front and back sheets, front and back walls arranged adjacent the front and back sheets, a pair of hollow water circulating and steaming elements, each open along one side, said open side being fixed in an associated side sheet so that it is inclined downwardly and inwardly transversely of the firebox and at an angle to the bottom of the side water leg longitudinally of the firebox, said elements being of less length than the distance between said front and back walls, thereby forming air feeding slots, and a burner positioned to discharge fuel for burning in suspension over said hollow water bottom. 10 15 20 25 30 35 40 45 50 55 60 65 70 75 80 85 90 95 100 105 110 115 120 125 130 135 140 145 150
10. A locomotive boiler embodying therein a firebox having side sheets defining the inner sides of side water legs and front and back sheets, front and back walls arranged adjacent the front and back sheets, a pair of hollow water circulating and steaming elements, each closed along one side and both ends and open along the other side and which latter is fixed in an associated side sheet so that it is inclined downwardly and inwardly transversely of the firebox and upwardly and rearwardly longitudinally of the firebox with respect to the bottom of the side water leg, said elements being of less length than the distance between said front and back walls, thereby forming air feeding slots, and a burner positioned to discharge fuel for burning in suspension over said hollow water bottom. 10 15 20 25 30 35 40 45 50 55 60 65 70 75 80 85 90 95 100 105 110 115 120 125 130 135 140 145 150
11. A locomotive boiler embodying therein a firebox having side water legs, a hollow water circulating and steaming bottom therefor, having portions which open into opposite side water legs, a firebox bottom closure extending across the firebox under and in spaced relation to the hollow water circulating and steaming bottom, thereby forming an air preheating chamber beneath the latter, a burner positioned to discharge fuel for burning in suspension over the hollow water circulating and steaming bottom, and openings for admitting air first into said preheating chamber and then into the combustion chamber. 10 15 20 25 30 35 40 45 50 55 60 65 70 75 80 85 90 95 100 105 110 115 120 125 130 135 140 145 150
12. A locomotive boiler embodying therein a firebox having side water legs closed at the bottom, a hollow water circulating and steaming bottom therefor having oppositely inclined transversely disposed portions which open into the side water legs, and which, longitudinally of the firebox, extend at an angle to the bottom closure of the side water legs, a closure extending across the firebox under and in spaced relation to the hollow water circulating and steaming bottom, thereby forming an air preheating chamber, a burner positioned to discharge fuel for burning in suspension over the hollow water circulating and steaming bottom, and an opening for admitting air from said preheating chamber to the combustion chamber. 10 15 20 25 30 35 40 45 50 55 60 65 70 75 80 85 90 95 100 105 110 115 120 125 130 135 140 145 150
13. A locomotive boiler embodying therein a firebox having side sheets defining the inner sides of water legs, a pair of hollow water circulating and steaming elements, each open along one side, said open side being fixed in an associated side sheet so that it is inclined downwardly and inwardly transversely of the firebox and at an angle

chamber underlying said elements and extending from end to end thereof.

18. A locomotive boiler embodying therein a firebox having side sheets defining the inner side 5 of side water legs, a pair of hollow water circulating and steaming elements each closed along one side and both ends and open along the other side which is fixed in an associated side sheet so as to extend downwardly and inwardly therefrom, 10 transversely of the firebox and longitudinally at an angle with respect to the bottom of the side water legs, with the closed sides of said elements in spaced relation, means bridging the space between said closed sides of said elements and 15 formed to provide longitudinally spaced air inlet openings therealong that open into the firebox and an air preheating chamber underlying said elements and extending from end to end thereof.

19. A locomotive boiler embodying therein a firebox having side sheets, a pair of hollow water 20 circulating and steaming elements, each closed along one side and open along the other side and which latter is fixed in an associated side sheet so that said element extends downwardly 25 and inwardly from said side sheets, the closed sides of said elements terminating in such spaced relation as to provide a longitudinal air slot of varying width and an air preheating chamber underlying said elements and extending from end 30 to end thereof.

20. A locomotive boiler embodying therein a firebox having side sheets, a pair of hollow water circulating and steaming elements each closed along one side and both ends and open along the 35 other side and which latter is fixed in an associated side sheet so that said element extends downwardly and inwardly therefrom, with the closed sides of said elements in spaced relation, to provide a longitudinal air inlet opening, a 40 burner wall and a flash wall at opposite ends of the firebox, one of said walls being spaced from the associated end of said elements to provide an air inlet slot between said one of said walls and said associated end of said elements.

45. 21. A locomotive boiler embodying therein a firebox having side sheets, a pair of hollow water circulating and steaming elements each closed along one side and both ends and open along the other side and which latter is fixed in an associated side sheet so that said elements extend 50 downwardly and inwardly therefrom, with the closed sides of said elements in spaced relation to provide a longitudinal air inlet opening, a burner wall and a flash wall at opposite ends of the firebox, both of said walls being spaced from the associated ends of said elements to provide air inlet slots between said walls and said associated ends of said elements.

60. 22. A locomotive boiler embodying therein a firebox having side sheets, a pair of hollow water circulating and steaming elements each closed along one side and both ends and open along the other side and which latter is fixed in an associated side sheet so that said element extends 65 downwardly and inwardly therefrom, with the closed sides of said elements in spaced relation to provide a longitudinal air inlet opening, a burner wall and a flash wall at opposite ends of the firebox, one of said walls being spaced from the associated end of said elements to provide an air inlet slot between said one of said walls and said associated end of said elements and means for controlling the area of said slot.

75. 23. A locomotive boiler embodying therein a

firebox having side sheets, a pair of hollow water circulating and steaming elements each closed along one side and both ends and open along the other side and which latter is fixed in an associated side sheet so that said element extends 80 downwardly and inwardly therefrom, with the closed sides of said elements in spaced relation to provide a longitudinal air inlet opening, a burner wall and a flash wall at opposite ends of the firebox, one of said walls being spaced from the associated end of said elements to provide an air inlet slot between said one of said walls and said associated end of said elements and means for controlling the width of said slot.

24. A locomotive boiler embodying therein a firebox having side sheets, a pair of hollow water circulating and steaming elements each closed along one side and both ends and open along the other side and which latter is fixed in an associated side sheet so that said element extends 85 downwardly and inwardly therefrom, with the closed sides of said elements in spaced relation, to provide a longitudinal air inlet opening, a burner wall and a flash wall at opposite ends of the firebox, one of said walls being spaced from the associated end of said elements to provide an air inlet slot between said one of said walls and said associated end of said elements and means for controlling the width of said slot.

25. A locomotive boiler embodying therein a firebox having side sheets, a pair of hollow water circulating and steaming elements each closed 95 along one side and both ends and open along the other side and which latter is fixed in an associated side sheet so that said element extends downwardly and inwardly therefrom, with the closed sides of said elements in spaced relation, to provide a longitudinal air inlet opening, a burner wall and a flash wall at opposite 100 ends of the firebox, one of said walls being spaced from the associated end of said elements to provide an air inlet slot between said one of said walls and said associated end of said elements and means carried by said associated end of said elements for controlling the width of said slot.

26. A locomotive boiler embodying therein a

firebox having side sheets, a pair of hollow water circulating and steaming elements each closed 110 along one side and both ends and open along the other side and which latter is fixed in an associated side sheet so that said element extends downwardly and inwardly therefrom, with the closed sides of said elements in spaced relation, to provide a longitudinal air inlet opening, a burner wall and a flash wall at opposite 115 ends of the firebox, both of said walls being spaced from the associated ends of said elements to provide air inlet slots between said walls and said associated ends of said elements and means for controlling the areas of said slots.

27. A locomotive boiler embodying therein a

firebox having side sheets, a pair of hollow water circulating and steaming elements each closed 125 along one side and both ends and open along the other side and which latter is fixed in an associated side sheet so that said element extends downwardly and inwardly therefrom, with the closed sides of said elements in spaced relation, to provide a longitudinal air inlet opening, a burner wall and a flash wall at opposite 130 ends of the firebox, both of said walls being spaced from the associated ends of said elements to provide air inlet slots between said walls and said associated ends of said elements, and means for controlling the width of said slots.

28. A locomotive boiler embodying therein a

said associated ends of said elements, and means carried by said associated ends of said elements for controlling the width of said slots.

28. A locomotive boiler embodying therein a firebox having side sheets, a pair of hollow water circulating and steaming elements each closed along one side and both ends and open along the other side and which latter is fixed in an associated side sheet so as to extend downwardly and inwardly therefrom, with the closed sides of said elements in spaced relation and refractory members resting at opposite sides on said closed sides of said elements to bridge the space between the same and formed to provide air inlet openings that open at opposite sides into the firebox.

29. A locomotive boiler embodying therein a firebox having side sheets, a pair of hollow water circulating and steaming elements each closed along one side and both ends and open along the other side and which latter is fixed in an associated side sheet so as to extend downwardly and inwardly therefrom, with the closed sides of said elements in spaced relation, means bridging the space between said closed sides of said elements and formed to provide longitudinally spaced air inlet openings therealong that open into the firebox, a burner and a flash wall at opposite ends of the firebox, both of said walls being spaced from the associated ends of said elements to provide air inlet slots for said ends of the firebox.

30. A locomotive boiler embodying therein a firebox having side sheets defining the inner side of side water legs which are bottomed by a mud ring, a pair of hollow water circulating and steaming elements, each closed along one side and both ends and open along the other side which is fixed in an associated side sheet so that said element extends downwardly and inwardly from said side sheets, with the closed sides in spaced relation, said elements also being inclined downwardly toward the front of the firebox with respect to said mud ring.

31. A locomotive boiler embodying therein a firebox having side sheets, a pair of hollow water circulating and steaming elements, each closed along one side and both ends and open along the other side and which latter is fixed in an associated side sheet so that said element extends downwardly and inwardly from said side sheets, the closed sides of said elements being in a spaced relation, to provide a longitudinal air inlet slot, said elements also being inclined downwardly toward the front of the firebox and a burner wall and a flash wall at opposite ends of the firebox, one of said walls being spaced from the associated end of said element to provide a transverse air inlet slot between said one of said walls and said end of said elements.

32. A locomotive boiler embodying therein a firebox having side sheets, a pair of hollow water circulating and steaming elements, each closed along one side and both ends and open along the other side and which latter is fixed in an associated side sheet so that said element extends downwardly and inwardly from said side sheets, the closed sides of said elements being in a spaced relation, to provide a longitudinal air inlet slot, said element also being inclined downwardly toward the front of the firebox and a burner wall and a flash wall at opposite ends of the firebox, both of said walls being spaced from the associated ends of said elements to provide transverse air inlet slots between said ends of said elements and said walls.

33. A locomotive boiler embodying therein a

firebox having side water legs bottomed by a mud ring, a pair of hollow water circulating and steaming elements each closed along one side and both ends and open along the other side and which latter is fixed in a side sheet of the firebox so as to communicate with an associated side water leg, said elements extending downwardly and inwardly from said side sheets, with the closed sides of said elements in spaced relation, the open sides of said element being arranged at an inclination to the horizontal as well as to plane of said mud ring to promote and direct circulation and also to provide a sludge pocket in said water leg which is deeper at the rear end than it is at the front end.

34. A locomotive boiler embodying therein a firebox having side sheets, a pair of hollow water circulating and steaming elements, each closed along one side and both ends and open along the other side and which latter is fixed in an associated side sheet so that said element extends downwardly and inwardly from said side sheets, the closed sides of said elements being in a spaced relation to form a longitudinal air inlet slot, a burner wall and a flash wall at opposite ends of the firebox, one of said walls being spaced from an associated end of said elements to provide a transverse air inlet slot between said one of said walls and said associated end of said elements, and means coacting with said elements to provide an air chamber beneath said elements and with which said air inlet opening and slot communicate.

35. A locomotive boiler embodying therein a firebox having side sheets, a pair of hollow water circulating and steaming elements, each closed along one side and both ends and open along the other side and which latter is fixed in an associated side sheet so that said element extends downwardly and inwardly from said side sheets, the closed sides of said elements being in a spaced relation, a burner wall and a flash wall at opposite ends of the firebox, both of said walls being spaced from the associated ends of said elements to there provide transverse air inlet slots and means coacting with said elements to provide an air chamber beneath said elements and with which said air inlet opening and slots communicate.

36. A locomotive boiler embodying therein a firebox having side sheets, a pair of hollow water circulating and steaming elements, each closed along one side and both ends and open along the other side and which latter is fixed in an associated side sheet so that said element extends downwardly and inwardly from said side sheets, the closed sides of said elements being in a spaced relation, a burner wall and a flash wall at opposite ends of the firebox, one of said walls being spaced from an associated end of said elements to provide a transverse air inlet slot between said one of said walls, and said associated end of said elements, means coacting with said elements to provide an air chamber beneath said elements and with which said air inlet opening and slot communicate, there being a primary air inlet in said burner wall opening into the firebox above said elements, and a fuel nozzle in said primary air inlet, there being secondary air inlets in said burner wall opening into said chamber.

37. A locomotive boiler embodying therein a firebox having side sheets, a pair of hollow water circulating and steaming elements, each closed along one side and both ends and open along the other side and which latter is fixed in an asso-

ciated side sheet so that said element extends downwardly and inwardly from said side sheets, the closed sides of said elements being in a spaced relation, a burner wall and a flash wall at opposite ends of the firebox, one of said walls being spaced from an associated end of said elements to provide a transverse air inlet slot between said one of said walls and said associated end of said elements, means coacting with said elements to 10 provide an air chamber beneath said elements

and with which said air inlet opening and slot communicate, there being a primary air inlet in said burner wall opening into the firebox above said elements, a fuel nozzle in said primary air inlet, there being secondary air inlets in said burner wall opening into said chamber and means for controlling the effective area of said secondary air inlets.

CHARLES GILBERT HAWLEY.
